PORTABLE RECEPTACLE

Rudolph Lobel, New York, N. Y., assignor to
 Friedman-Lobel, Inc., New York, N. Y., a corporation of New York

Application June 5, 1935, Serial No. 25,044

9 Claims. (Cl. 150—29)

This invention relates to portable receptacles, and has particular reference to devices such as handbags and toilet kits.

One object of this invention is the provision of a device of the character described having a wall structure, parts of which are movable in opening and closing the receptacle, and a frame in improved coordination therewith and serving to stretch the wall structure about the frame in 5 to stretch the wall structure about the frame in 10 a body shaping and forming cooperation when the receptacle is closed and to release the body structure, in part, when the receptacle is open, whereby a neat, inexpensive structure is produced with a minimum of fabrication.

Another object of the invention is to furnish 15 a device of the type mentioned having a framed receptacle which permits of the maximum degree of opening, substantially greater than that heretofore obtained, and yet in a simple, and reliable manner and with a minimum number of 20 connections of the frame and receptacle.

Another object of the invention is to provide a device of the class alluded to having a receptacle of improved arrangement and design, permitting 25 all parts thereof to be readily accessible, and permitting the opening of only one part of a single main compartment thereof, if desired.

Another object of the invention is to provide 30 a device having a framed receptacle, the frame whereof has improved expanded closure walls for the receptacle.

Another object of the invention is to construct 35 a device of the character mentioned whereby a frame co-operates to produce a tight lock joint at an end of a receptacle, preferably in cooperation with a gusset supported thereby, and which may therefore be of different sizes, and designs, and need not be inherently tight.

Other objects and advantages of the invention 40 will become apparent as the specification proceeds.

With the aforesaid objects in view, the invention consists in the novel combinations and arrangements of parts hereinafter described in 45 their preferred embodiments, pointed out in the subjoined claims, and illustrated in the annexed drawing, wherein like parts are designated by the same reference characters throughout the several views.

In the drawing:

Figure 1 is a view in front elevation showing in closed position a device embodying the invention.

Fig. 2 is a view in end elevation thereof, with a 55 part removed.

Fig. 3 is a top plan view of the same in full open position.

Fig. 4 is an end view thereof.

Fig. 5 is a top plan view of the device in partly open position.

Fig. 6 is a sectional view taken on the vertical line 6—6 of Fig. 3.

Fig. 7 is a sectional view taken on the vertical line 7—7 of Fig. 4.

Fig. 8 is a fragmentary perspective isometric view of the frame.

Fig. 9 is a fragmentary perspective isometric view showing details of a gusset connection.

Fig. 10 is a fragmentary perspective isometric view of a modification of the invention.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 11 denotes a device embodying the invention. The same may include a receptacle, bag, or container made of any suitable material and preferably comprising a plurality of walls, such as opposite side walls 12, 13. The wall 12 may include a plurality of wall portions 14, 15 which are connected individually to the side wall 13 as by means of top and bottom wall portions 16, 17. The side wall 35 portions 14, 15 are movable toward and away from each other, as by reason of the flexibility of the walls 13, 16 and 17, for closing and opening the receptacle. Gussets 18 may be connected to the walls 13 to 17 at each end of the receptacle, 40 these gussets being infoldable and being desirably of less height than the side wall portions 14 and 15. Preferably, the wall portion 15 may be of greater height than the companion portion 14, and the gussets may taper to correspond.

In the closed position of the receptacle, the wall portions 14, 15 may lie in the same plane and with their free or leading edges in abutment with each other as shown at 19. In that position, the gussets 18 are infolded substantially as 50 shown in Fig. 5, and obviously the ends of the receptacle would be substantially open since the gussets would lie substantially parallel to the side walls 12, 13, and unless articles were secured under the gussets, such articles might drop out 55

and be lost. However, small articles could readily slip from under the gussets and fall out at the ends of the receptacle. Furthermore, the pliable wall structure and gussets would have no 5 definite form or body, and to build the receptacle into such definite body and shape would materially increase the cost of manufacture and require special, complicated gusset fastenings.

By my invention, I overcome these difficulties 10 by providing a frame structure having a minimum of connection with the receptacle walls, so as to require little mechanical fabrication, and nevertheless acting as a body forming means for the receptacle, as a support for the gussets especially when the receptacle is open, and as a 15 reliable joint locking means for the ends of the receptacle.

Thus I employ at each end of the receptacle a plurality of frame members such as 20, 21, connected to the side wall portions 14, 15 as at the 20 free or leading edges thereof, for instance, to the channels 22, 23 clamped on the edges of the respective wall portions 14, 15. Cooperating with the frame members 20, 21 is a body forming portion or frame member 24 to which the members 20, 21 may be pivotally connected as at 25, 26 25 at the ends of the member 24. The latter may be relatively wider than the members 20, 21 and may extend substantially the full length of the receptacle with the ends rounded as at 27 to 30 conform to the receptacle. In the closed position of the device 11, the frame members 20, 21 may lie in alinement with each other and in the same plane with the member 24, along which 35 they extend from end to end of the receptacle. Thus the free ends of the frame members 20, 21 may abut each other along the plane of the line 19.

To provide a reliable joining or closure interengagement, and for mutual reenforcement between the members, the frame members 20, 21 may constitute channels, and the member 24 may constitute a plane strip or blade element receivable in part in the channels of the members 20, 21. The members 20, 21 and 24 constitute an 40 expandible end wall allowing for a degree of expansion of the receptacle, as by the yielding of a locking device hereinafter described, or by the bulging action of the receptacle due to its contents, and nevertheless maintaining an end closure when the receptacle is closed. The channel interengagement serves to reenforce the frame especially at the leading edges, in closed position.

When the receptacle is in open position, as 45 shown in Fig. 4, the frame parts 20, 21 and 24 maintain the frame members 22, 23 in parallelism in a fairly rigid relationship to each other. Since the frame members 20, 21 and 24 lie outside of the gussets 18, the same are afforded at least 50 partial support. Due to friction at the joints 25, 26, the receptacle is held open.

Upon closing the receptacle, the side walls 13, 14, 15 are drawn around the frame parts 20, 21 and 24, which they overlie, as particularly 60 shown in Fig. 3, so that the receptacle is stretched about the frame with the pull being communicated thereto at the channels 22, 23. Hence the receptacle walls snugly fit around the frame structure as shown in Fig. 2, assuming a definite 65 shape and body.

The receptacle may be opened only in part as indicated in Fig. 5, and if desired, the wall 15 may be little used or may be relatively permanently closed. In any case, the gussets are directed inwardly and are shaped in that manner

by the elements 20, 21 as shown in Fig. 7 at 29. It is seen from Fig. 9, that the securement of the gussets to the side walls begins at a point 30 below the connection of the frame parts 22, 23 with elements 20, 21, as at 31 to facilitate the 5 infolding of the gussets.

Any one of the frame parts 20, 21 and 24 may be considered as the body forming portion as each part is necessary in drawing the receptacle wall structure around the frame.

The frame members 23 may have stop elements 32 secured thereto to underlie the member 22, and maintain the members in the same plane. A resilient catch 33 may be connected to the member 22 and may have an undercut hook 34 to 15 engage and releasably snap under a correspondingly hooked lug or pin 35 fixed to the element 23 and thus to prevent the wall 14 from being moved upward without first upwardly springing the element 33.

In Fig. 10 is shown a modification of the invention embodying in a handbag certain of the principles hereinbefore disclosed, and having the body forming advantages, neatness, and permitting a wide opening of the bag receptacle with 25 the use of shorter gussets if desired.

Thus the device 40 may include a bag 41 having a conventional top closure flap 42 for the opening 43 thereof, and having opposite end gussets 44. Frame channels 45, 46 are secured 30 to free edge portions of the bag, and the channel 45 may connect the flap 42 to the bag, if desired. A relatively wide body forming frame member 47 which may be of plane sheet metal may be cut out at 48a to fit member 45 and 35 to be rigidly secured thereto. A channel member 48, or the like, may be rigidly secured to member 46 at 49a, and may be pivoted to 47 as at 49. The member 47 may be undercut at 50 to provide a portion engageable in the channel member 48, with the parts when engaged 40 affording a tight closure, permitting the use of a short gusset 44, and drawing the bag snugly around the frame so that the bag snugly engages around the members 47, 48. Thus the bag may 45 be opened more widely than heretofore possible, and the end gussets are not alone relied upon for tightness of the bag. It will be understood that the same arrangement may be used at both ends of the bag.

It will be noted that in both of the devices 11 and 40, the frame structure is separate of the bag except for its connection with the free edges thereof.

The different frames may be variously shaped, 55 for example, somewhat conically as in the device 11, and the joints 25, 26 may have suitable clearance for the pivotal movement of the parts and interengagement of the frame members as required.

It will be appreciated that various changes and modifications may be made in the device as shown in the drawing, and that the same is submitted in an illustrative and not in a limiting sense, the scope of the invention being defined 65 in the following claims.

I claim:

1. A portable receptacle having a first side wall and a second side wall, the latter comprising a plurality of side wall portions connected to the first 70 side wall for swinging movement relative thereto about generally parallel lines, the side wall portions being movable toward and away from each other to close and open the receptacle, the side walls being tapered in one direction in the closed posi- 75

tion of the receptacle and one side wall portion having a greater average length than the other side wall portion, gussets at the ends of the receptacle interconnecting the said side wall portions with the first side wall, the gussets folding inwardly and the side wall portions folding downwardly upon the gussets upon closing the receptacle, the receptacle having a generally box like form when the receptacle is fully open with the side wall portions being upright, frame elements connected to the side wall portions along the leading edges thereof, and frames at the ends of the receptacle external of the gussets, each frame comprising channel frame members connected to the frame elements and extending upright in the full open position of the receptacle, a blade loosely pivotally connected at its ends to the channel frame members and lying in relatively close proximity to the first side wall in the open position of the receptacle, the channel members conforming to the said tapered shape of the receptacle and the blade being guidingly engageable in the channel members about the said loose pivotal connections when the receptacle is closed, the said frames being otherwise independent of the gussets and of the first and second side walls, the said side walls being tensioned about the frames in the closed position of the receptacle with the frames constituting end closures therefor, and means for releasably maintaining the receptacle in closed position.

2. A portable receptacle including a foldable upwardly tapered bag which in full open position is of generally box-like form and comprises a bottom wall, upright side walls and gusseted end walls, with one side wall being generally longer than the other and one side wall tapering upwardly, and frames for the ends of the bag in tapered relation to each other to conform to the shape of the bag, each frame comprising a plurality of channel members and a blade member, the channel members extending along the side walls and the blade member along the bottom wall, the ends of the channel members and of the blade member being loosely pivotally interconnected with the blade member adapted to be guidingly engaged in the channel members when the bag is closed, and the said side walls being tensioned about the frames in the closed position of the receptacle with the frames constituting end closures for the receptacle, and means for holding the receptacle closed.

3. A portable receptacle including a bag having its ends tapered upwardly in closed position, said bag in full open position being of generally box-like form and comprising a bottom wall, upright side walls and gusseted end walls with one side wall having an average length greater than that of the other side wall and one side wall having its ends tapering toward each other in a different direction than the ends of the other side wall, channel frame elements in which the free edges of the side walls are clamped, and frames for the ends of the bag tapering relative to each other to conform to the shape of the bag, each frame having a plurality of members including blade and channel members, a plurality of the members being rigidly connected to the respective frame elements in offset relation thereto and being upright in said open position of the bag, another of said members being in relative proximity to said bottom wall and being so loosely pivotally connected to the ends of the upright members as to be adapted to be guidingly engaged with the upright members on closing

the bag, whereby creasing of the side walls is avoided when the bag is open and the said frame elements lie in edge to edge abutment when the bag is closed.

4. A portable receptacle including a bag which in full open position is of generally box-like form having a large bottom wall, upright side walls and gusseted end walls, frames for the ends of the bag connected to the side walls at the leading edges thereof and being otherwise free of the bag, each of said frames having a plurality of channel members and a blade member pivotally interconnected so as to be engageable in the channel members upon closing the bag, said channel members extending upright along the side walls in the said full open position of the receptacle and the blade member lying spaced above but in relative proximity to the bottom wall and affording lateral external support to the gusseted end walls, whereby the gusseted end walls are foldable away from the frames so as not to catch therein immediately upon initiating a closing movement of the bag.

5. A portable receptacle including a bag which in full open position is of generally box-like form with a large bottom wall, upright side walls and gusseted end walls, the side walls being foldable downwardly and the gusseted walls being foldable inwardly, channel elements in which the leading edges of the side walls are secured, and frames for the ends of the bag, each frame comprising at least three members, two of which are connected to the frame elements in inwardly offset relation thereto and extending upright in said full open position of the bag, and the third member extending along the bottom wall and being pivotally connected at its ends to the lower ends of the first named members so that the latter are swingable downward upon closing the bag, said members having interfitting blade and channel interengagement in the closed position of the bag, and said members being otherwise free of the bag.

6. A portable receptacle including a bag which in full open position is of generally box-like form having a large bottom wall, upright side walls and gusseted end walls, frames for the ends of the bag connected to the side walls at the leading edges thereof and being otherwise free of the bag, each of said frames having a plurality of channel members and a blade member pivotally interconnected so as to be engageable in the channel members upon closing the bag, said channel members extending upright along the side walls in the said full open position of the receptacle and the blade member lying spaced above but in relative proximity to the bottom wall and affording lateral external support to the gusseted end walls, said blade members being of substantially greater width than the channel members, and the points of said pivotal interconnection between the members being remote from the lower edge of the blade members.

7. A portable receptacle including a bag which in full open position is of generally box-like form with a large bottom wall, upright side walls and gusseted end walls, the side walls being foldable downwardly and the gusseted walls being foldable inwardly, channel elements in which the leading edges of the side walls are secured, and frames for the ends of the bag, each frame comprising at least three members, two of which are connected to the frame elements and extending upright in said full open position of the bag, and the third member extending along the bottom

- wall and being pivotally connected at its ends to the lower ends of the first named members so that the latter are swingable downward upon closing the bag, said members having interfitting 5
blade and channel interengagement in the closed position of the bag, and said members being otherwise free of the bag including the gusseted end walls thereof, the bottom and side walls of the bag being tensioned around the frames with 10
the members thereof in the said interfitting relation constituting continuous end closures for the bag, and releasable locking means for the bag.
8. A portable receptacle including a bag having 15
side walls movable toward and away from each other, end gussets interconnecting the side walls, frame elements connected to the side walls along the leading edges thereof, end frames each of which includes a relatively wide plate and a relatively narrow arm pivotally interconnected remotely from the frame elements and being connected at their upper ends to the frame elements for movement into and out of engagement with each other upon corresponding 20
movement of the side walls, said frames being otherwise free of the gussets and the side 25
walls and lying externally of the gussets and extending the full length and width of the bag to constitute end closures for the bag when the side walls are moved toward each other.

9. A device including a receptacle having side walls interconnected at the bottom and being movable toward and away from each other, rigid frame elements connected to the side walls along the free edges thereof, and frames at the ends of the receptacle lying wholly between end marginal portions of the side walls, each frame including a plate member extending from the top to the bottom of the receptacle and being rigidly connected at the top to a frame element, and a frame arm for each end frame, said frame arm 15
being pivotally connected at its lower end to a plate member intermediate of the ends thereof for movement toward and away from the plate member, and said arm being rigidly connected at its upper end to the other frame element for 20
movement therewith, and the frames being otherwise separate of the receptacle, and constituting end closures for the receptacle upon movement of the arms into engagement with the plate members. 25

RUDOLPH LOBEL.
